UNITED STATES PATENT OFFICE.

PHILIP H. SENIOR, OF NEW YORK, N. Y.

SPRING-SEPARATOR.

1,170,565.

Specification of Letters Patent.

Patented Feb. 8, 1916.

Application filed May 1, 1914. Serial No. 835,601.

To all whom it may concern:

Be it known that I, PHILIP H. SENIOR, a citizen of the United States, and resident of the city, county, and State of New York, 5 have invented certain new and useful Improvements in Spring-Separators, of which the following is a specification.

This invention relates to a device adapted to be used as a spring separator, the object 10 being to provide a simple device to separate the leaves of an ordinary flat spring for the purpose of inserting a lubricant between the same or for the other purposes.

In carrying out the invention I provide a 15 device in which there are no moving parts and which, on account of its simple construction, may be cheaply manufactured but is extremely efficient for the purpose above indicated and easily operated.

20 In the drawings like parts in the several views have been given the same reference numerals.

Figure 1 is a plan view of the device, showing the same in its operative position 25 with relation to the spring. Fig. 2 is a side elevation, partly in section, of the device as shown in Fig. 1. Fig. 3 is an end elevation of the device as shown in Fig. 1. Fig. 4 is a side elevation of the device, showing the 30 operative parts mounted in a different position.

The handle 1, preferably made of a flat strip of metal, forms a relatively long lever bent upwardly at one end, as shown in 2. 35 At this end of the device operating members 3 and 4 are secured by means of one or more bolts such members remaining fixed and stationary upon the handle during operation of the device.

40 The operating members 3 and 4 are preferably formed from a flat strip of metal bent into a hook-shape and mounted upon the handle 1 with their upper ends extending inwardly toward each other, as shown in Fig. 3. These inwardly extending ends of the 45 operating members 3 and 4 are tapered down to relatively sharp edges and preferably hardened. The lower portions thereof may be provided with one or more holes for the 50 fastening bolts or with slots to provide for adjustment of the same to accommodate springs of different widths. In the construction as shown, the member 3 is provided with a single hole and the member 4 with a 55 slot, for the purpose specified. The operating members 3 and 4 are positioned on the

handle 1 so as to abut against the bent end 2 of the same, thus preventing the members from turning and permitting the use of a single bolt for securing the same for the 60 handle in a substantial manner.

In operation the device is placed against the spring with the inwardly extending sharp edges of the members 3 and 4 against the adjacent edges of the spring leaves. The 65 operating handle is then moved to one side or the other angularly with respect to the spring, in a plane substantially parallel to the contacting surfaces of the leaves to be separated, into an angular position with 70 reference to the leaves, as shown in Fig. 1, causing the sharp edges of the members 3 and 4 to enter between the leaves and separate the same, as will be readily understood. 75

In order to provide greater ease and accessibility when used with springs of different forms, the operating members 3 and 4 may be mounted in a different angular position on the handle 1 as shown in Fig. 4 and 80 operated in the same manner as that just described.

It will thus be seen that a very simple construction is provided for a device of this nature, which is not only efficient and simple 85 in its operation for this or any other purpose but which may be very cheaply manufactured.

I do not wish to be understood as confining my invention to the exact details of construction shown and described, as it will be obvious that the same may be modified without departing from the purpose and scope of the invention as defined in the appended claims. 90 95

What I claim is:

1. A device of the class described, comprising a relatively long handle lever, and a pair of operating members fixed and stationary upon said lever, said operating 100 members having wedge portions facing inwardly toward one another and adapted to enter between the leaves of a spring when said lever is moved angularly with relation to the spring in a plane substantially parallel to the contacting surfaces of the leaves to be separated. 105

2. A device of the character described, comprising a relatively long handle lever, and a pair of hook shaped operating members fixed and stationary upon said lever, said operating members having their 110

hooked ends terminating in wedge portions facing inwardly toward one another and adapted to enter between the leaves of a spring when said lever is moved angularly 5 with relation to the spring in a plane substantially parallel to the contacting surfaces of the leaves.

3. A device of the class described, comprising a relatively long handle lever, a 10 pair of operating members fixed and stationary upon said lever, said operating members having wedge portions facing inwardly toward one another and adapted to enter between the leaves of a spring when 15 said lever is moved angularly with relation to the spring in a plane parallel to the contacting surfaces of the leaves to be separated, and means whereby said operating members may be adjusted upon said lever to vary the distance between the said wedge shaped portions.

4. A device of the class described, comprising a relatively long handle lever having a shoulder formed at one end, a pair 25 of operating members mounted thereupon and having portions adapted to enter between the leaves of a spring to separate said leaves, said operating members engaging said shoulder to prevent turning movement 30 of the operating members with respect to

the said lever, and means securing said operating members upon said lever.

5. A device of the class described, comprising a relatively long handle lever, a pair of operating members fixed and stationary upon said lever, said operating members having wedge portions facing inwardly toward one another and adapted to enter between the leaves of a spring to 35 separate said leaves, and means whereby 40 said operating members may be secured in different angular positions upon said lever.

6. A device of the class described, comprising a handle bent at one end to form a shoulder, a pair of hook shaped operating 45 members having inwardly extending ends either or both of which are tapered to sharp edges to enter between the leaves of a spring to separate said leaves, and means whereby 50 said operating members may be secured upon said handle in position extending either transversely or longitudinally thereof, said operating members abutting against said shoulder in both of said positions.

Signed in the city, county and State of 55
New York, this 28th day of April, 1914.

PHILIP H. SENIOR.
